UNITED STATES PATENT OFFICE

2,605,317

ONE-PIECE ELECTRIC LIGHT SOCKET

Anthony Tiscione, Brooklyn, N. Y.

Application July 16, 1948, Serial No. 39,145

3 Claims. (Cl. 173—358)

1

This invention relates to new and useful improvements in light bulb sockets, and, more particularly, the aim of the invention is to provide a novel and valuable socket characterized by the fact that the socket is formed as a one-piece body of dielectric plastic material, carrying, as elements anchored in situ in the body during the molding thereof, the two conductive terminals for engaging a bulb inserted into the socket and for placing such bulb in circuit with a suitable source of electric current.

Thereby an exceedingly inexpensive, long-lived and dependably functioning socket, and one ideally adapted for use in Christmas tree lighting, is provided.

By the present invention, not only are such additional parts as terminal screws or other specially to be manipulated connecting means entirely dispensed with, an advantage which is obtainable pursuant to the proposal of my earlier Patent No. 2,466,566 granted April 5, 1949, but also, in lieu of the plural part socket body disclosed in my earlier Patent No. 2,534,804 granted December 19, 1950, there is provided the one-piece body aforesaid. As proposed in the earlier of my prior patents, bared or stripped sections of insulated wires are used in connection with the socket body, yet these do not have to be inserted into the body after the making thereof, but, according to the present invention, these wires, at bared portions thereof, are the elements which provide the socket terminals and which as above stated are the elements anchored in situ in the one-piece socket body during the molding thereof.

A feature of the present invention is that in thus anchoring said wires in the socket body, they are preferably anchored in said body by embedding therein not only of the said bared portions of the wires but also at wire portions adjacent to said bared portions, with the result that parts of the insulative sheathing of the wires are also embedded in said body. This fortifies the anchorages of the socket terminals, and, furthermore, insurance is had that no portion of a wire beyond the exterior of the socket body will ever accidentally become bared.

Modifications of the present invention propose arrangements wherein metallic clips are mounted upon the parallel wires at spaced points along the length thereof in a manner to have the one-piece sockets molded upon the wires with the clips exposed within bulb receiving openings of the sockets so that when bulbs are screwed into the bulb receiving openings, the terminal contacts of the bulbs will make a good electrical

2

contact with the metallic clips mounted on the wires.

It is a further object of the present invention to construct the clips so that they will have 5 prongs pressed into the insulation in a manner to hold the metallic clips in position on the wires and to make a good electrical contact with the metallic wire strands encased within the insulation without requiring baring of the strands.

It is a further object of the present invention to construct a one-piece light bulb socket which is simple and durable and which may be manufactured and sold at a reasonable cost.

15 For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a top perspective view of a one-piece 25 lamp socket body constructed in accordance with the present invention and particularly well adapted for use in connection with Christmas tree illumination.

Fig. 2 is a vertical sectional view taken on the line 2—2 of Fig. 1.

30 Fig. 3 is also a vertical sectional view taken on the line 3—3 of Fig. 2.

Fig. 4 is a horizontal sectional view taken substantially on the line 4—4 of Fig. 2.

35 Fig. 5 is a vertical section illustrating a modification.

Fig. 6 is a detail elevational view, showing fragmentarily a possible type of wire which could be used.

Fig. 7 is a similar view, showing another possible type of wire which could be used.

Fig. 8 is a diagrammatic view, showing in dot and dash various ones of a string of socket bodies anchored to a pair of wires by being 45 molded about the latter at spaced bared portions of both said wires and at suitable intervals along the length thereof.

Fig. 9 shows a three-part mold for thus molding a socket body about bared portions of two wires, this view being mainly a vertical section taken on the line 9—9 of Fig. 10.

Fig. 10 shows said mold, but with one of the 50 three parts thereof, said part shown in top plan and also shown as being partially withdrawn in Fig. 9, shown as fully entered into the main mold

cavity; this view being a vertical section taken on the line 10—10 of Fig. 9.

Fig. 11 is a view similar to Fig. 2, but showing a further modification.

Fig. 12 is a vertical sectional view similar to Fig. 2, but illustrating the one-piece socket body constructed in accordance with a modification of the invention.

Fig. 13 is an enlarged perspective view of one of the parallel wires used in the form of the invention shown in Fig. 12.

Fig. 14 is a sectional view taken on the line 14—14 of Fig. 13.

Fig. 15 is a perspective view of one of the metallic clips, per se.

Fig. 16 is another vertical sectional view similar to Fig. 2, but illustrating the one-piece socket body constructed in accordance with a still further modification of the invention.

Fig. 17 is a side elevational view of one of the parallel wires used in the form of the invention shown in Fig. 16.

Fig. 18 is a sectional view taken on the line 18—18 of Fig. 17.

Fig. 19 is a plan view of the metallic clip per se.

Referring to the drawings more in detail, and first to Figs. 1—4, 15 denotes the socket body as a whole, the same being shown as having an interior at the top of which is a short cylindrical neck 16, below which is a threaded portion 17 for taking the base of a bulb having a screw-base, and below the threaded portion 17 a chamber 18 shaped to receive the lower end of said base with the central lowermost button-like terminal thereof at the bottom of said chamber. The threaded portion 17 is employed in lieu of the ordinary brass or other metal portion or part included in the usual socket for contacting the matching threaded metallic side wall of the screw-like base of an ordinary bulb.

The socket body 15 as illustrated in Fig. 1 is shown as provided with an added fitment 19 to adapt the socket for convenient use in Christmas tree lighting, which fitment or equivalent may be attached in any suitable way to the socket body 15 after the molding thereof, as by a screw applied to a threaded recess in the bottom of said body and matchable with an aperture through the foot portion 19' of said fitment, or, if desired, said fitment or an equivalent may be integrated with the socket body by having its said foot portion or an equivalent portion embedded in situ in said body during the molding thereof.

The form of the invention now being described is one wherein the new socket body is one to be used with a plurality of others thereof, for connection in parallel, as is desirable in Christmas tree lighting. Therefore, the two wires 20 and 21 having bared portions thereof to be anchored in situ in the socket body during molding of the latter are shown as extending all through the body. It will be noted, further, that the length of the wire 20 thus extended through the body 15 includes a bared section 20^a and two portions 20^b and 20^c of the wire where covered with insulative sheathing; and that the length of the wire 21 thus extended through the body 15 includes a bared section 21^a thereof and two portions 21^b and 21^c of the wire where covered with insulative sheathing.

The portions 20^a, 20^b and 20^c of the wire 20 are shown as arranged substantially horizontally across the socket body 15, but so that, with the portion 20^a preferably slightly obliquely inclined, at an angle substantially corresponding to the

pitch angle of the thread 17, said portion 20^a extends over a suitable distance along a fraction of one turn of said thread in such manner that said portion 20^a in effect lies in and forms part of the groove between an adjoining pair of turns of the thread, when such thread is molded at the portion 17 of the body 15. At the same time, the bared portion 20^a of the wire 20 is of short enough length to insure that the portions 20^b and 20^c of the wire 20 are irremovably buried in the body 15 at its wall portions lying outwardly of its said portion 17.

The portions 21^a, 21^b and 21^c of the wire 21 are also shown as arranged horizontally across the socket body 15, with the bared portion 21^a, as to the entirety of its thickness or as to the upper part of its thickness, exposed substantially horizontally of the bottom of the chamber 18, and with the portions 20^b and 20^c of said wire, inclusive of the insulative sheathing thereon, irremovably buried in the body 15 at its wall portions opposite said chamber bottom.

Fig. 5 illustrates a variation, in that with one wire, as the wire 20' corresponding to the wire 20, is extended substantially horizontally in one direction across the body 15' corresponding to the body 15, the wire 21' corresponding to the wire 21 is extended horizontally through said body 15' with the direction of extension of this wire at an angle to the direction of extension of the wire 20' such angle here shown, by way of example, as approximately a right angle.

As indicated in Figs. 6 and 7, respectively, a wire used pursuant to the invention may comprise an insulative sheathing with a conductor core or wire proper either of solid type or of the braided type.

In Fig. 8, a plurality of socket bodies are shown as strung at suitable intervals along a pair of wires 20 and 21, with one bared portion and two insulatively sheathed or covered portions of each wire embedded in each body pursuant to the invention, as, for instance, explained in connection with Figs. 1—7.

Referring to Figs. 9 and 10, illustrative more or less diagrammatically of a molding machine unit for producing the new socket body, and for use also if desired for successively adding to the two wires said socket bodies one after the other, said unit is shown as comprising a basal part 22, this having a suitable gate 23 for admission of the plastic material, as by injection, an upper separable part 24, and a third part 25 for spiral advance into and similar withdrawal from, the main mold cavity, as indicated by the arrow 26; such main cavity being marked 27, and being partially carried by the part 22 and partially carried by the part 24. The separation plane of said parts 22 and 24, shown in Fig. 10, is in accordance with the line A—B of Fig. 3.

Also in the said molding unit are minor cavities, these for receiving the insulated portions of the wires which are to immediately adjoin the insulated portions of the wires to be embedded in the socket body. Said minor cavities are four in number, all of cylindrical cross-section for snugly fitting about the sheathing on the wires at portions therealong just outwardly of the portions thereof to be embedded together with the sheathing in the socket body.

Two of said minor cavities are respectively marked 28 and 29, with the lower halves of these carried by the basal part 22 and with their top halves carried by the upper part 24. In Fig. 9, 75 a wire, with its insulated portions placed in the

minor cavities 28 and 29, so as properly to extend into the main mold cavity 27 the bared portion of said wire and also insulated portions thereof immediately adjoining opposite end limits of said bared portion, is indicated in dot and dash at 30.

The other two of said minor cavities are respectively marked 31 and 32, also with the lower halves of these carried by the basal part 22 and with their top halves carried by the upper part 24. In Fig. 9, a wire, with its insulated portions placed in the minor cavities 31 and 32, so as properly to extend into the main mold cavity the bared portion of said wire and also insulated portions thereof immediately adjoining opposite end limits of said bared portion, is indicated in dot and dash at 33.

In order to position said bared wire portion of the wire 31 properly relative to the thread to be molded in the socket body by the threaded portion 34 of the mold part 25, the upper mold part 24 has a pair of depending transverse ribs 35 and 35', each of these fittable into a recess, such as the one indicated in Fig. 10 at 36, in the basal mold part 22; and each of the minor cavities 31 and 32 has the top half, thereof, at the bottom of one of said ribs and the bottom half thereof at the bottom of the appropriate recess.

Referring to Fig. 11, here the invention is shown as applied, in one of a possible variety of ways, to provide a socket body 15' wherein the bared portions of the wires embedded therein are at the ends of said wires; so that the socket body is served in use by a pair of wires solely allotted thereto. These wires, marked 37 and 38, have embedded in the socket body their insulation covered portions 37^a and 38^a, and in addition thereto merely their bared end portions 37^b and 38^b. As here shown, the portions last-mentioned have bent terminal shapings as shown, for setting up a positive interlock with the molded socket body. The bared terminal portions of both wires may, to this end, be shaped either as shown in the case of the wire 37 or as shown in the case of the wire 38 or otherwise equivalently bent.

In the modification of the invention shown in Figs. 12 to 15, the construction of the one-piece socket body is similar to that shown in Figs. 1 and 2, except that instead of baring portions of the parallel wires 40 and 41, each is provided, at points where they pass through the socket body 15, with metallic clips 42 exposed within the hollow of the socket body 15 to be engaged by the terminal contacts of an electric light bulb engaged within the socket body 15.

Each of the metallic clips 42 is alike in construction and is provided at its ends with pointed portions 43 pressed through the insulation of the wires 40 and 41 to engage the strands of the wire encased within the insulation. Thus it is apparent that the pointed portions 43 serve the dual purpose of anchoring the metallic clips 42 in position upon the wires and also completing the electrical circuit from the metallic strands encased within the insulation of the wire to the terminals of the light bulb.

In other respects this form of the invention is similar to the first form of the present invention and like reference numerals identify like parts in each of the several views.

In the modification of the invention shown in Figs. 16 to 19, the construction of the one-piece socket body is similar to that shown in Figs. 12 to 15, differing only in the formation of the metallic clips 42', and like reference numerals are used to identify like parts.

In this form of the invention the metallic clips 42' mounted on the parallel wires 40 and 41 are longitudinally curved to extend obliquely over about one-half of the insulation of the wires. The pointed portions 43' extend from the ends of the clips 42' so as to enter the insulation of the wires from opposite sides thereof. With this construction good electrical contact is made with the strands of wire encased within the insulation and the metallic clips 42' are more securely anchored in position upon the wires 40 and 41.

The invention has been described as used in connection with a light bulb, but it is not to be thus limited, as the new socket will function just as well in connection with any inserted electrical device, for example, a so-called plug. In the appended claims, the term "insert" is used as inclusive of such a plug, a light-bulb base (whether of the screw-base or other type; unless otherwise stated in a particular claim), or any electrical device to be, or having a part to be, inserted in an electric socket.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. An electric socket comprising a one-piece body molded of a dielectric material and formed with a bulb receiving opening for the threaded portion of an electric light bulb, parallel electric wires having outer insulation casings and molded within said body and having portions exposed at spaced points within said bulb receiving opening, and metallic clips mounted on the portions of said wires exposed within said bulb receiving opening to make electrical contact with the terminals of a light bulb screwed in position in said opening, said metallic clips being curved longitudinally to extend obliquely over about one-half of said wires, said clips being formed at their ends with pointed portions piercing the insulation casings of the wires from diametrically opposite sides and making electrical contact with wire strands enclosed within said insulation casings.

2. An electric socket comprising a one-piece body molded of insulation material, said body having a threaded recess for threadedly receiving the threaded base portion of an electric light bulb, parallel electric wires having outer insulation casings enclosing wire strands and molded within said body and having portions exposed within spaced points of said recess, and metallic clips mounted on the portions of said wires exposed within said recess to make electrical contact with the terminals of a light bulb screwed into position within said recess, said clips being elongated and bent longitudinally to extend about one-half the circumference of said wires, and means at the ends of said clips securing said clips in position on said wires and piercing said insulation casings to make electrical contact with said wire strands.

3. An electric socket comprising a one-piece body molded of insulation material, said body having a threaded recess for threadedly receiving the threaded base portion of an electric light bulb, parallel electric wires having outer insulation casings enclosing wire strands and molded within said body and having portions exposed

within spaced points of said recess, and metallic clips mounted on the portions of said wires exposed within said recess to make electrical contact with the terminals of a light bulb screwed into position within said recess, said clips being elongated and bent longitudinally to extend about one-half the circumference of said wires, and means at the ends of said clips securing said clips in position on said wires and piercing said insulation casings to make electrical contact with 10 said wire strands, said securing means comprising pointed portions formed on the ends of said metallic clips and extended toward one another to pierce said insulation casings from opposite sides and engage said wire strands.
